Patented Nov. 18, 1913.

UNITED STATES PATENT OFFICE.

CHESLEY GORDON, OF LOS ANGELES, CALIFORNIA.

DEVICE FOR AUTOMATICALLY CUTTING OFF THE SUPPLY OF GAS TO A BURNER.

1,079,122.

Specification of Letters Patent. Patented Nov. 18, 1913.

Application filed March 7, 1912. Serial No. 752,760.

To all whom it may concern:

Be it known that I, Chesley Gordon, a citizen of the United States, residing at Los Angeles, in the county of Los Angeles and State of California, have invented new and useful Improvements in Devices for Automatically Cutting Off the Supply of Gas to a Burner, of which the following is a specification.

10 An object of the invention is to provide a device for automatically cutting off the supply of gas to a burner.

The invention embodies, among other features, a device which can be used in connection with the burner of a stove or with the usual burner employed on chandeliers or other similar members for illuminating purposes, and whereby the supply of gas to the burner can be cut off by the action of the 26 heat produced at the burner.

In the further disclosure of the invention reference is to be had to the accompanying drawings, constituting a part of this specification, in which similar characters of reference

25 denote corresponding parts in all the views, and in which:

Figure 1 is a side elevation of the device showing the same in applied position, parts being broken away to disclose the underlying structure and parts being shown in vertical section; Fig. 2 is a horizontal sectional view taken on the line 2--2 in Fig. 1; and Fig. 3 is a horizontal sectional view taken on the line 3--3 in Fig. 1.

35 Referring more particularly to the views, I disclose a valve casing 10 provided with a valve chamber 11 having a gas inlet 12 and an outlet 13, the casing 10 having connection with a gas supply pipe 14 and supported 40 thereby, with the said supply pipe terminating at the inlet 12 of the casing 10, a second pipe 15 having connection with the outlet 13 and extending downwardly to terminate in a burner 16 provided with the usual hand 45 operable cock 17.

An end of the outlet 13 is normally closed by a plug 18 supporting a horizontal bearing 19 in which is mounted to slide a vertically operable rod 20 encircled by an expandible 50 spring 21 having one end thereof abutting against the bearing 19 and the other end thereof abutting against a disk 22 secured

rigidly on the rod 20, thus normally retaining the rod in an uppermost position. A reduced end 23 of a bracket 24 is received in 55 the plug 18 and has threaded connection therewith so that the plug 18, aside from closing an end of the outlet 13, supports the bearing 19 and rod 20 and also the bracket 24, the said bracket being extended downwardly and terminating adjacent to and slightly below the burner 16.

A vertical expansion rod 25 has threaded connection with the lower end of the bracket 24 and is provided with a knurled handle 26 65 whereby the rod 25 may be moved vertically with respect to the bracket, thus providing for an adjustment of the rod for a purpose that will be hereinafter more fully disclosed, it being further seen that the rod is arranged to extend vertically adjacent the burner 16 so that when a flame is produced by the gas issuing from the burner the heat of the flame will tend to heat the expansion rod 25 and cause the same to expand longitudinally.

A vertically operable stem 27 is mounted on the casing 10 and extends through the valve chamber 11 of the casing, a valve 28 being carried on the said stem in the said 80 valve chamber and adapted to normally repose on a valve seat 29 formed in the casing, the upper end of the said stem being engaged by an expandible helical spring 30 carried in the casing 10 and adjustable by 85 means of a suitable screw 31 threaded in the casing and provided at one end with a disk 32 abutting against the spring 30 so that the tension of the spring can be increased or decreased to exert a greater or 90 less downward pressure on the stem 27, the lower end of the said stem being provided with a recess 33 in which is normally received the free end of the expansion tube 25, the said free end of the expansion tube being 95 preferably pointed as shown. Mounted to swing on the bracket 24 is a lever 34 having pivotal connection with the lower end of the rod 20 and having the other end thereof adapted to abut against a pin 35 projecting 100 laterally from the stem 27. An operating cord 36 also has connection with the rod 20 at the point of pivotal connection of the rod with the lever 34, the said cord being adapt-

1 to depend a slight distance below the burner 16, it being understood that the lever 34 can be either actuated by pushing down on the rod 20 or by pulling on the cord 36. 5 A pilot tube 37 has connection with the valve chamber 11 and extends downwardly and terminates adjacent the burner 16, a valve 38 being carried by the pilot tube 37 for controlling the supply of gas thereto. 10 When the valve 28 is reposing on the valve seat 29 and thus preventing the gas in the supply pipe 14 from passing into the pipe 15 and thence to the burner, the stem 27 will be in lowermost position and 15 will be held in this position by the expansible action of the spring 30. When it is desired to produce a flame at the burner 16, a downward pull is exerted on the cord 36, it being understood, however, that a 20 downward push on the rod 20 will accomplish the same result, and in consequence thereof the lever 34 will be actuated so that an end of the lever will engage the pin 35 and impart an upward movement to the 25 stem 27, thus unseating the valve 28 and permitting the gas to pass through the casing 10, into the pipe 15 and then to the burner 16 where the gas will be ignited by the pilot flame at the lower end of the 30 pilot tube 37 and which receives its supply of gas from the valve chamber 11. When the flame at the burner 16 has heated the expansion tube 25 sufficiently to cause the same to expand longitudinally and abut 35 against the lower end of the stem 27, the downward pull on the cord 36 is released and it will thus be seen that the expansion of the rod 25, and by means of which the tube engages the stem 27, retains the valve 40 28 in open position so that a constant supply of gas will pass from the supply pipe 14 to the burner 16. Now if for any reason the pressure in the gas main should be reduced, the flame at the burner 16 will of 45 course be diminished and as a result thereof, if the pressure is entirely cut off, the expansion rod 25 will cool and contract, the spring 30 will move the stem 27 downwardly and move the valve 28 into closed 50 position to cut off the supply of gas to the burner.

From the foregoing description it will therefore, be apparent that the escape of gas into a room, will be prevented in view 55 of the fact that whenever all pressure is reduced or cut off so as to result in the extinguishing of the flame at the burner, the valve 28 will be moved into closed position and cut off the supply of gas, to the burner, 60 it being further seen, however, that by simply exerting a pull on the cord 36, the gas will again be conveyed to the burner to produce a flame at that point and as long as the pressure is not reduced in the gas main 65 the flame at the burner will continue.

Having thus described my invention, I claim:

1. In a device of the class described, the combination with a casing provided with an inlet and an outlet, of a gas supply having 70 connection with the inlet of the casing, a pipe having connection with the outlet, a burner carried by the pipe, a stem mounted to slide in the said casing, a valve carried by the stem to normally close a passage between the inlet and the outlet, a bracket supported on the casing, a lever mounted to swing on the bracket, a pin projecting from the stem and adapted to be engaged by the said lever to actuate the stem and unseat 80 the said valve in the said casing, and an expansion rod adjustably supported on the said bracket and projecting vertically adjacent the said burner to engage the said stem when the said rod is extended. 85

2. In a device of the class described, the combination with a casing provided with a valve chamber and having an inlet and an outlet, with the said casing attached to a gas supply terminating in the said inlet, of 90 a pipe connected to the casing at the outlet thereof and depending below the casing, a burner carried by the pipe, a bracket supported on the casing, a stem slidable in the said casing and depending exteriorly 95 thereof, a valve carried by the stem and normally closing a passage between the inlet and outlet in the said casing, an expansion rod adjustably supported on the said bracket adjacent the said burner, with the upper end 100 of the expansion rod engaged by the lower end of the said stem, a lever mounted to swing on the said bracket, a pin projecting from the stem and adapted to be engaged by the lever when the same is actuated to 105 move the said stem to unseat the said valve, and means for operating the said lever.

3. In a device of the class described, the combination with a casing provided with a valve chamber and having an inlet and an 110 outlet, with the said casing attached to a gas supply terminating in the said inlet, of a pipe connected to the casing at the outlet thereof and depending below the casing, a burner carried by the pipe, a bracket supported on the casing, a stem slidable in the said casing and depending exteriorly 115 thereof, a valve carried by the stem and normally closing a passage between the inlet and outlet in the said casing, an expansion 120 rod adjustably supported on the said bracket, adjacent the said burner, with the upper end of the expansion rod engaged by the lower end of the said stem, a lever mounted to swing on the said bracket, a pin projecting from the stem and adapted to be engaged by the lever when the same is actuated to 125 move the said stem to unseat the said valve, means for operating the said lever, a spring carried in the casing and 130

engaging the stem to normally retain the valve in closed position in the casing, and a means for adjusting the said spring, and a pilot tube supported on the casing and dependent therefrom, with the free end of the pilot tube arranged adjacent the said burner.

In testimony whereof I affix my signature in presence of two witnesses.

CHESLEY GORDON.
